UNITED STATES PATENT OFFICE.

DANIEL S. EVERETT, OF JORDAN, NEW YORK.

SASH HOLDER.

Application filed February 26, 1926. Serial No. 90,790.

The present invention relates to sash holders and more particularly to the type in which a wedge member is mounted to move so as to hold the sash in any desired position in a window frame. An object of this invention is to provide a surface with which the wedge member may engage in moving to its holding position, said surface being mounted to move to adapt itself to a surface on the wedge. A further object of the invention is to provide a novel means of moving the wedge member toward and from holding position.

To these and other ends, the invention consists of certain parts and combinations of parts, all of which will be hereinafter described, the novel features being pointed out in the appended claims.

In the drawings:

Fig. 1 is a fragmentary view of a sash and a window frame showing the sash holder in the position it occupies when the sash is free to move;

Fig. 2 is similar view showing the sash holder in holding position; and

Fig. 3 is a sectional view through the sash showing the sash holder in side elevation in the position illustrated in Fig. 1.

Referring more particularly to the drawings, 1 indicates the window frame and 2 the sash. In this instance, the sash holder is illustrated as being mounted on the sash, but it will be understood that the invention is not limited to this position. The holder, in this instance, embodies a wedge member 3 having two faces 4 and 5 at angles to each other other than right angles. This wedge member may be moved toward and from wedging position by an eccentric 6 pivoted at 7, in this instance, to the sash and having an eccentric surface 8 cooperating with a shoulder 9 formed on the upper part of the wedge member. The wedge member has an extension 10 projecting above said shoulder which is adapted to limit the movement of the eccentric 6 in one direction, the eccentric, in this instance, having an extension or operating arm 11 which is extended therefrom to cooperate with the extension 10. The eccentric surface 8 cooperates with the shoulder 9 and depresses the wedge 3 to holding position. In order to withdraw the wedge from holding position the eccentric has a link 12 pivoted at an eccentric point 13 thereto and formed with a slot 15 which receives a headed projection 16 on the wedge member. It is

apparent that with the swinging of the eccentric 6 through the arm 11, the link 12 will ride on the headed projection 16 through the slot 15, but with the swinging of the eccentric member upwardly, the end of the slot 15 will cooperate with the headed projection 16 and elevate the wedge member 3.

The wedge member preferably cooperates with a block or member 17 which has a straight line face 18 cooperating with the straight line face 5 of the wedge member 3. The straight line face 18 is arranged at an angle other than a right angle to the line of movement of the sash and this is also true of the straight line face 5 of the wedge member. The straight line face 4 of the wedge member is substantially parallel with the line of movement of the sash. The member 17 is pivoted at 19 between the two ends of its straight line face preferably to the sash 2. As a consequence, the member 17 rocks on the pivot 19 and the face 18 adapts itself to the position of the wedge member. This arrangement makes it unnecessary to accurately position the member 17 on the sash and makes it possible to obtain binding engagement between the wedge member 3 and the member 17 throughout the length of the two cooperating faces, while, at the same time, obtaining binding engagement between the member 3 and the part of the window having relative movement to said member, so that the face 4 of the member 3 will lie parallel with the surface with which said member engages to hold the sash against movement.

In order to permit the free movement of the sash, the operating eccentric or cam 7 is moved to the position shown in Fig. 1, drawing the wedge member 3 upwardly and away from the frame of the window. To hold the window sash in an adjusted position the cam or eccentric 6 is turned through the arm 11 to the position shown in Fig. 2, forcing the wedge member downwardly into engagement with the face 18 of the member 17 and with the adjacent position of the window frame.

What I claim as my invention and desire to secure by Letters Patent is:

1. A sash holder comprising a wedge having two surfaces at angles to each other other than right angles, one of said surfaces being adapted to cooperate with a part to hold the sash in an adjusted position, a rocking member having a straight line surface for co-

operating with the other surface of the wedge when the latter is in holding position and means for moving said wedge into engagement with the rocking member including a pivoted eccentric engaging said wedge.

2. A sash holder comprising a wedge having two surfaces at angles other than right angles to each other, one of said surfaces acting to engage a part to hold the sash in adjusted position, another member having a surface adapted to be engaged by the other surface of the wedge when the wedge is in holding position, and means for operating said wedge comprising an eccentric having a portion adapted to engage the wedge, and a link pivotally connected to the eccentric at a point eccentric to the turning axis of the latter and having a pin and slot connection with the wedge member.

3. A sash holder comprising a wedge member having two faces at angles to each other other than right angles, one of said faces cooperating with a part to hold the sash in an adjusted position, said wedge member having a shoulder and a projection beyond said shoulder, a pivotally mounted eccentric arranged to engage said shoulder and having an arm adapted to cooperate with the extension on the wedge member to limit the movement of the eccentric in one direction, a connecting link between the eccentric and the wedge member for moving the latter away from holding position, and a member cooperating with the other face of the wedge member to force the wedge member into engagement with a part to hold the sash against movement.

DANIEL S. EVERETT.
